RETRIEVING CARRIAGE FOR SPAN BRACKETS

Filed Oct. 23, 1948

UNITED STATES PATENT OFFICE

2,500,996

RETRIEVING CARRIAGE FOR SPAN
BRACKETSWinford Gladstone Milne, Hamilton, Ontario,
Canada, assignor to N. Slater Company Lim-
ited, Hamilton, Ontario, Canada

Application October 23, 1948, Serial No. 56,230

6 Claims. (Cl. 254—124)

1

This invention relates to retrieving carriages for transposition brackets as quite commonly used for transposing the conductors used in communication or carrier current circuits. Such brackets are usually positioned somewhere between a pair of poles or towers and may be located in desired position by looping a rope through or around the bracket and pulling it along the conductor wires to the desired point after which the rope is unroved by letting loose of one side of the loop and pulling on the other. The transposition bracket will now be in such a place as to render it difficult, if not impossible, to rereeve the rope.

It is the principal object of the present invention to provide a novel retrieving device capable of being placed on and drawn along the wires carrying the transposition bracket to engage and move the latter.

A second important object of the invention is to provide a novel retriever carriage having a tilting hook engageable with the disengageable from a transposition bracket when both the bracket and the carriage are supported on the same pair of wires.

A third important object of the invention is to provide a novel form of retrieving carriage having a tilting hook wherein the carriage is adapted to be supported on a pair of wires and drawn therealong and wherein the hook is moved into position of engagement with a transposition bracket on said wires upon the carriage being drawn in one direction along said wires.

With the above and other objects in view, as will be presently apparent, the invention consists in general of certain novel details of construction and combinations of parts hereinafter fully described, illustrated in the accompanying drawings, and particularly claimed.

In the accompanying drawings like characters of reference indicate like parts in the several views, and:

Fig. 1 is a plan view of the invention.

Fig. 2 is a section on the line 2—2 of Fig. 1.

Fig. 3 is a section on the line 3—3 of Fig. 2 and showing the retrieving hook in one position.

Fig. 4 is a section similar to Fig. 3 but showing the retrieving hook in a second position.

In the embodiment of the invention as herein disclosed there is provided a substantially rectangular frame having parallel side bars 10 which are connected at the front end by a front cross bar 11 and at the rear end by a rear cross bar 12. At the junction of the side bars with the front and rear bars are inverted U-shaped guide mem-

bers 13 each of which has a somewhat flared mouth 14 so that these guide members may rest and readily slide along the wires W.

Depending from the front bar 11 at the center thereof is a pair of spaced ears 15 wherethrough passes a pin 16. On the pin 16 is mounted a tilting member 17 so slotted as at 18 as to form a generally link like structure having an upper longitudinal side 19 and a lower longitudinal side 20. The front ends of the upper and lower sides are straight as can clearly be seen by reference to Figs. 3 and 4, while the rear ends of the sides 19 and 20 are curved from their junction with the straight portions rearwardly and upwardly as can also be seen by Figs. 3 and 4. The upper side 19 is extended as at 21 to form an upwardly extending and rearwardly bent hook and at the junction of the straight and curved portions of the upper member 19 there is provided a boss 22 wherethrough passes the pin 16 so that the hook member 17 may rock on this pin. From the boss 22 there extends upwardly a pair of spaced stop members 23 which are adapted to engage a fixed stop 24 extending between the upper portions of the ears 15. Slideable in the slot 18 is a link 25 and this link has, in operation, a rope or cable 26 attached thereto.

When the tilting member 17 is in the position shown in Fig. 3 the link 25 will be in position to draw the carriage forwardly along the wires W until the hook portion 21 is in position for engagement with a portion of the span transposition bracket shown in broken lines at B in Fig. 4. When this position has been attained the rope or cable 26 will be shifted until it inclines toward the pole to which it is desired to bring the span transposition bracket. The shifting in this manner, as shown in Fig. 4, will cause the hook 21 to swing upwards and engage a transverse portion 40 of the bracket B and a continuous pull on the cable 26 in the direction indicated in Fig. 4 will then cause the transposition bracket to move along with the retrieving carriage until it has reached a position enabling the linesman to operate on such transposition bracket, the linesman being at the top of a pole.

Then the retrieving hook may be detached from the transposition bracket and if desired may be carried to the pole from the direction in which movement of the transposition bracket has been affected by what has just been described. When placed in this relation to the transposition bracket the retrieving carriage may again be drawn toward the bracket with the link 25 near the hook 21 until engagement can again be

affected between the hook and transposition bracket whereupon shifting as before of the link away from the hook would cause engagement of the hook so that the carriage and bracket may be pulled out to the same position as before or any other position desired.

In some instances it may be found desirable to line the members 13 with insulation so that the flow of current between the two wires W will be prevented.

What is claimed is:

1. A transposition bracket retrieving carriage including a frame, means to support said frame on a pair of wires, a tilting hook mounted on said frame said hook being provided with a downwardly curved slot extending from end to end thereof, and means to draw said carriage in either direction along said wires and to simultaneously effect tilting of the hook between bracket engaging and disengaging positions said means including a link slidable from end to end of said slot and a draw line attached to said link and effecting movement of the link from end to end of the slot and thereby tilting of the tilting member.

2. A transposition bracket retrieving carriage including a frame, means to support said frame on a pair of wires, a tilting hook mounted on said frame said hook being provided with a downwardly curved slot extending from end to end thereof, means to draw said carriage in either direction along said wires and to simultaneously effect tilting of the hook between bracket engaging and disengaging positions said means including a link slidable from end to end of said slot and a draw line attached to said link and effecting movement of the link from end to end of the slot and thereby tilting of the tilting member, and means to limit tilting movement of said hook.

3. A transposition bracket retrieving carriage including a rectangular frame having a transversely extending front bar, wire riding elements at the corners of said frame, a pair of spaced ears projecting downwardly from said front bar, a pivot pin extending between said ears, a tilting member pivoted on said pivot said hook being provided with a downwardly curved slot extending from end to end thereof, a bracket engaging hook at the front end of the tilting member, and means to draw said carriage along the wires on which it rides and to simultaneously effect tilting of said member and cause said hook to move between bracket engaging and disengaging positions said means including a link slidable from end to end of said slot and a draw line attached to said link and effecting movement of the link from end to end of the slot and thereby tilting of the tilting member.

4. A transposition bracket retrieving carriage including a rectangular frame having a transversely extending front bar, wire riding elements at the corners of said frame, a pair of spaced ears projecting downwardly from said front bar, a pivot pin extending between said ears, a tilting member pivoted on said pivot said hook being provided with a downwardly curved slot extending from end to end thereof, a bracket engaging hook at the front end of the tilting member, means to draw said carriage along the wires on which it rides and to simultaneously effect tilting of said member and cause said hook to move between bracket engaging and disengaging positions said means including a link slidable from end to end of said slot and a draw line attached to said link and effecting movement of the link from end to end of the slot and thereby tilting of the tilting member, and means to limit tilting movement of said hook.

5. A transposition bracket retrieving carriage including a rectangular frame having a transversely extending front bar, wire riding elements at the corners of said frame, a pair of spaced ears projecting downwardly from said front bar, a pivot pin extending between said ears, a tilting member pivoted on said pivot said hook being provided with a downwardly curved slot extending from end to end thereof, a bracket engaging hook at the front end of the tilting member, said tilting member having a longitudinal slot therein, and a rope engaging link engaging in and slidable from end to end of said slot.

6. A transposition bracket retrieving carriage including a rectangular frame having a transversely extending front bar, wire riding elements at the corners of said frame, a pair of spaced ears projecting downwardly from said front bar, a pivot pin extending between said ears, a tilting member pivoted on said pivot said hook being provided with a downwardly curved slot extending from end to end thereof, a bracket engaging hook at the front end of the tilting member, said tilting member having a longitudinal slot therein, a rope engaging link engaging in and slidable from end to end of said slot, and means to limit tilting movement of said hook.
